CLAIM

The ornamental design for a headgear for a breathing apparatus, as shown and described.

DESCRIPTION

FIG. 1 is a perspective view showing front, top and side surfaces of a headgear for a breathing apparatus, which embodies our design.

FIG. 2 is a perspective view showing rear, bottom and side surfaces thereof.

FIG. 3 is a front view thereof.

FIG. 4 is a rear view thereof.

FIG. 5 is a top view thereof.

FIG. 6 is a bottom view thereof; and,

FIG. 7 is a right side view thereof, the left side being a mirror image of the right side.

1 Claim, 6 Drawing Sheets
